MACHINE FOR MANUFACTURING MOLDED PULP ARTICLES

Merle P. Chaplin, South Portland, Maine, assignor to Chaplin Corporation, Portland, Maine, a corporation of Maine

Application March 18, 1942, Serial No. 435,163

23 Claims.

(Cl. 92—56)

My invention relates to a machine for manufacturing molded pulp articles, and covers a unitary arrangement of mechanism for forming, drying and finishing molded pulp products. Molded products of various sizes and shapes can be produced by the mechanism of this invention from a liquid pulp mixture, the mechanism combining the wet forming or felting of an article on a contoured die from this mixture, the delivering of the wet felted article to drying mechanism, and the drying and finishing of the article to accurate size and shape and with a smooth surface on one or both sides, the finished article being printed and discharged automatically from the machine.

In the preferred embodiment of the invention I provide a forming unit which has a step-by-step rotation about a horizontal axis and carries a plurality of radially disposed arms on which are dies which are successively immersed in a liquid pulp mixture while suction or vacuum is applied to the interior of the immersed die, whereby a layer or deposit of pulp fiber is drawn onto its surface and the free water or other liquid is drawn away.

Ordinarily, these forming dies are, after being accurately contoured to the shape of the desired articles, covered with a fine mesh wire cloth which allows the water or other liquid from the pulp mixture to pass through the cloth, leaving the pulp fiber deposited in a layer thereon.

After a sufficient quantity of pulp fiber has been deposited on the surface of the forming die, the die is removed from the pulp mixture by a periodic rotation of the forming unit.

The exposed surface of the pulp deposit is preferably seared by the application of a heated die. This is not a necessary part or function of the machine, but is preferable and useful as is hereinafter described. While one of the forming dies is being drained and, if desired, the article surface seared, a second forming die has been moved into the vat and is receiving a pulp deposit on its surface.

A second periodic movement of the forming unit brings the arm upon which the article with the seared surface is supported into a vertical position in axial alignment with one of a pair of drying and finishing dies to which it is transferred. The drying and finishing dies are parts of a drying unit which has a step-by-step rotation about a vertical axis. These pairs of dies are equally spaced angularly and one of each

pair is so mounted that during the period in which an article is being transferred to it, it is moved out of axial alignment with its complementary die.

After the article is dried it is discharged onto a transfer die of another unit where it may be printed and finally discharged from the machine.

The transfer of an article from one unit to another is accomplished during the periods of the stepping cycle in which the units are at rest between rotative steps in their rotation with the proper dies in coactive alignment with each other.

All coacting units of the machine may be driven step-by-step by suitable mechanism, such as Geneva gearing, to move the units in required synchronism with each other.

The actuation of the various dies as required may be accomplished either mechanically, by air, hydraulically or by a combination of such means.

Suitable air and vacuum connections are provided to the various dies, as required, and the timing of the air and vacuum to these dies is properly synchronized.

Heat may be applied to the searing die and to the various drying dies by the use of heater plates to which the dies are removably attached.

Continued stepping of the drying unit brings the upper drying die to which the article has been transferred into axial alignment with its mating drying die. The drying dies are then moved together with the wet article between them and remain in continued pressure contact with the article during the drying of the article and until the continued step-by-step rotation of the drying unit brings the dies to an angular position, where it is necessary to retract the upper drying die with the finished article on it from the lower drying die to permit the drying dies in the continued step-by-step rotation of the machine to be moved out of mutual alignment so that the finished article may be discharged.

While the drying dies are out of axial alignment the upper drying die is again lowered to bring the article onto a die of a discharge unit to which it is transferred as by a blast of air and on which it may be printed and from which it may be conveniently removed by a conveyor.

In the accompanying drawings I have illustrated a preferred embodiment of my invention, together with some modifications suggestive of the many variations which are within the scope of the invention.

Referring to the drawings,

Fig. 1 is a sectional elevation of a machine which is made according to and embodies my invention. This section is taken on the line 1—1 of Fig. 2;

Fig. 2 is a plan view of the machine shown in Fig. 1;

Fig. 3 is a sectional plan view of the machine, the section being taken on the line 3—3 of Fig. 1;

Fig. 4 is a sectional elevation of the machine, the section being taken on the line 4—4 of Fig. 1;

Fig. 5 is an enlarged section showing a forming die and a searing die in cooperative positions;

Fig. 6 is a similar view of a forming die and an upper drying die;

Fig. 7 is a similar section through a pair of drying dies;

Fig. 8 is a sectional elevation of the discharge unit, showing one of the printing mechanisms. The section in this figure is taken on the line 8—8 of Fig. 2;

Fig. 9 is a plan view of another mechanism for imparting this desired movement to the upper drying dies.

10 designates a base upon which the various parts of the machine are mounted. 11 is a drive shaft to which is affixed an arm 12 on which is a pin or roller 13 which engages radial slots 14 in a disk 15 which is keyed to a longitudinal shaft 16 mounted in suitable bearings on the base 10 whereby an intermittent rotation is imparted to the shaft 16.

20 is a hollow housing keyed to shaft 16 between a stationary suction box 21 and an air pressure box 22. Four hollow arms 23 are shown extending radially from the housing. A greater or less number of such arms may be provided. These arms carry on their ends perforated forming dies 25 which are immersed successively in a liquid pulp mixture in a vat 17 in the base 10. At the time one of the forming dies is immersed in the pulp mixture it is connected through its hollow supporting arm 23 with the suction box 21 through suitable ports in a well known manner. The die is brought to rest in this position which is shown in Fig. 1 in the vat 17 and some of the pulp mixture accumulates on it.

The forming die is constructed as shown in Fig. 5. The end of each arm 23 forms a housing 24 to which the die 25 is affixed, as by screws 26, 27. The body of this forming die is accurately contoured to the shape of the desired article and covered with a fine mesh wire cloth 28 clamped to the housing at 29 which allows water or other liquid to pass through perforations 29 in the body, leaving a layer of the pulp fiber on the wire cloth.

A ninety degree rotation is then imparted to the shaft 16 in an anti-clockwise direction as viewed in Fig. 4. This brings another forming die into the vat 17 and moves the arm of the die first described into a horizontal position and into axial alignment with a heated searing die 30.

The die 30 has a surface 31 (Fig. 5) which is shaped to conform to the article on the forming die and is arranged to compress and heat the surface of the material on it. The die 30 is mounted on a hollow heater plate 32 which is made according to the teachings of my patent No. 2,206,276, issued July 2, 1940, to which steam or other heating medium may be admitted through a pipe 33 through which the condensate may run off. Entrapped air may escape through a vent 34. As shown in the drawings this searing die is imperforate. The die is attached to

the heater plate by a bolt 35 which passes through a central opening 36 through the heater plate. A gasket 37 under the head of the bolt closes the outer end of the opening 36. The die 30 is forced up to the forming die by some suitable means, as by a piston in a hydraulic cylinder 38. Heating and compressing the outer surface of the article compacts and partially dries a portion of the article forcing the moisture and vapor through the wire screen 27, perforations 29 into the housing 24 from which they are drawn off into the suction box 21. The outer surface of the article is thus rendered denser and firmer than the remainder of the article and this restricts the escape of fusible and volatile matter therethrough during the final drying operation hereafter described.

After the article has been thus heated and compressed the die 30 is retracted and another quarter revolution is imparted to the shaft 16 to bring the arm 23 which bears the seared article into a vertical position. It is then in axial alignment with an upper drying die 40 which is then in the position n which it is shown at A in Fig. 2. (See also Fig. 6.) The upper drying dies are supported on arms 51 which extend radially from a rotatable hollow shaft 50 and are connected to the arms by auxiliary arms 52. A bracket 53 extends upwardly from each auxiliary arm and carries a roller 54 which engages a cam track 55 (Figs. 1 and 4) which determines the radial distance of the upper drying die from the axis of the shaft 50. The lower part of the shaft is a hollow cylindrical body 56 which is mounted to rotate in a correspondingly shaped post 18 of the base 10.

Each upper drying die is mounted as shown in Fig. 6 on a hollow heater plate 60 which comprises a chamber 61 into which steam or other heating medium may be admitted through a pipe 62. In this case a flexible pipe 63 is connected with a radial passage which leads to the central opening 64, and passages 41 in die 40 interconnect the opening 64 with an annular passage 42 in the die 40 which in turn is in communication with the face of the die through openings 43 which may be in the form of radial slots.

When the forming die 25 and the upper drying die 40 are in axial alignment in the position A of Fig. 2, the upper drying die is moved down onto the article on the forming die, as shown in Fig. 6, by some suitable mechanism such as a piston in a hydraulic cylinder 44. The article is then transferred to the upper drying die by admitting air under pressure into the forming die through the hollow arm 23 and applying a partial vacuum to the upper drying die through the pipe 63. Then the upper drying die 40 is raised by the piston in cylinder 44. This operation takes place while the shaft 50 is at rest.

60 A partial rotation is then imparted to the shaft 50 by a Geneva gear which comprises an arm 58 on a shaft which is connected to the drive shaft 11 by gears 57 and which carries a pin or roller 59 which runs into slots 58 on a disk 59 affixed to the shaft 50.

70 This partial rotation and the partial retraction effected by the roller and cam track brings the upper drying die into the position in which it is shown at B in Fig. 2. In this position it is in axial alignment with a lower drying die 70 on a heater plate 71. The heater plates for the lower drying dies are supported on rigid brackets 72 which extend radially from the shaft 50. 73 is a pipe for leading steam to these heater plates.

When the upper drying die 46 reaches the position B it is forced down onto a complementary lower drying die by the piston in the cylinder shown in Fig. 7. Vacuum is still maintained in the upper drying die through the pipe 63. Parts of the article will be impressed into the slots 43 to form small ribs on the finished article and give it a distinct and attractive appearance.

The drying dies remain in this position with the article compressed between them during subsequent rotational steps of the drying unit. If desired, a vacuum may be applied to the lower drying die during this period. When the drying dies reach the position C (Fig. 2), the upper drying die is raised with the article on it. During the next rotational step, from the position C to the position D, the upper drying die is moved outwardly beyond its complementary lower drying die by the cam 55, and is then forced downwardly to one of the dies 80 of the discharge unit. There are four of these dies mounted on hollow shafts 81 extending radially from a shaft 82 to which an intermittent rotation is imparted in synchronism with the forming and drying units by mechanism not shown. Air and vacuum may be applied to the dies 80 in the manner described in connection with the forming unit. After the article has been transferred from the upper drying die onto a discharge unit die, the upper drying die is raised and then rotated to the position A (Fig. 2), over a forming die. During this rotational movement the die 80 with the article on it is rotated to the position 80A. Here it may be printed.

For the purpose of printing, a die 83 may be reciprocated by a piston in a cylinder 84. Inking rolls 85 are reciprocated between the die 83 and an inking pad 86 by a piston in a cylinder 87. When the die 80 reaches the position in which it is shown in Fig. 2, it may be printed again, inking rollers and an inking pad being shown at 85A and 86A.

Each discharge die 80 is pivoted to its respective arm 81 at 88 and when an arm reaches such a position as that shown at 88C in Fig. 8, its die is turned over as shown at 88C and the article drops off of it. A conveyor 89 may be provided to carry the article away from the machine.

In Fig. 9 the upper drying dies and the cylinders which impart vertical movement to them are mounted on tracks 98 which are parts of the rotary drying unit and guide these drying dies radially. Cylinders 91 which are mounted radially on the shaft 50 contain pistons which are connected with the upper drying dies by rods 92. By introducing a fluid into the cylinders 91 at times properly synchronized with the movements of the machines, the upper drying dies are moved radially into and out of register with their complementary lower drying dies.

Other modifications may be made within the spirit and scope of this invention and I intend no limitations other than those imposed by the appended claims. It is obvious that this application discloses a novel method which is not claimed and the right to file a divisional application to cover it is reserved.

What I claim is:

1. A pulp molding machine comprising a shaft, means for imparting a step-by-step rotation thereto, a plurality of pairs of drying dies mounted on the shaft in angularly spaced relation and rotating with the shaft, means for imparting a relative lateral movement to the dies of each pair to put them out of axial alignment with each

other, one of said dies of each pair being arranged to receive a wet formed article while out of axial alignment with its mating die, said moving means being arranged to return the dies into axial alignment, and means for imparting relative axial movement to the dies to compress the wet article between them.

2. A pulp molding machine comprising a shaft, means for imparting a step-by-step rotation thereto, a plurality of pairs of drying dies mounted on the shaft in angularly spaced relation and rotating with the shaft, means for imparting a relative lateral movement to the dies of each pair to put them out of axial alignment with each other, one of said dies of each pair being arranged to receive a wet formed article while out of axial alignment with its mating die, said moving means being arranged to return the dies into axial alignment, means for imparting relative axial movement to the dies to compress the wet article between them and for separating the dies, and means for discharging the article while the dies are out of axial alignment.

3. A pulp molding machine comprising a shaft, means for imparting a step-by-step rotation thereto, a plurality of pairs of drying dies mounted on the shaft in angularly spaced relation and revolving with the shaft, the dies of each pair being arranged to move in a common path in axial alignment with each other during a substantial portion of the rotating cycle of the shaft, means for imparting a relative lateral movement to the dies of each pair to put them out of axial alignment with each other during another portion of the rotating cycle of the shaft, one of the dies of each pair being arranged to receive a wet formed article while out of alignment with its mating die, said moving means being arranged to return the dies into axial alignment, and means for imparting relative axial movement to the dies to maintain the article between them under compression during said substantial portion of the rotating cycle of the shaft.

4. A pulp molding machine comprising a shaft, means for imparting a step-by-step rotation thereto, a plurality of pairs of drying dies mounted on the shaft in angularly spaced relation and revolving with the shaft, the dies of each pair being arranged to move in a common path in axial alignment with each other during a substantial portion of the rotating cycle of the shaft, means for imparting a relative lateral movement to the dies of each pair to put them out of axial alignment with each other during another portion of the rotating cycle of the shaft, one of the dies of each pair being arranged to receive a wet formed article while out of alignment with its mating die, said moving means being arranged to return the dies into axial alignment, means for imparting relative axial movement to the dies to maintain the article between them under compression during said substantial portion of the rotating cycle of the shaft and for separating the dies, and means for discharging the article while the dies are out of axial alignment.

5. A pulp molding machine comprising a shaft, means for imparting a step-by-step rotation thereto, a first series of drying dies and a second series of complementary drying dies mounted on the shaft in angularly spaced relation and rotating with the shaft, one of said series being connected with the shaft to travel in a circular path, means for guiding the other series of dies in the same circular path during a substantial portion of the rotating cycle of the shaft in axial

alinement with the complementary series of dies and for guiding said other series of dies laterally out of said circular path during another portion of the rotating cycle of the shaft, each of the dies of one of said series being arranged to receive a wet formed article when it is out of said circular path, said guiding means being arranged to return the dies into axial alinement and means for imparting relative axial movement to the complementary dies when the dies are in axial alinement to maintain the article between them under compression while the dies move in the circular path.

6. A pulp molding machine comprising a shaft, means for imparting a step-by-step rotation thereto, a series of upper drying dies and a like series of lower drying dies mounted on the shaft in angularly spaced relation and rotating with the shaft, said lower series being connected with the shaft to travel in a circular path, means for guiding the upper series of dies in the same circular path during a substantial portion of the rotating cycle of the shaft in axial alinement with the lower series of dies and for guiding the upper series of dies laterally out of said circular path during another portion of the rotating cycle of the shaft, each of the dies of the upper series being arranged to receive a wet formed article when it is out of said circular path, said guiding means being arranged to return the dies into axial alinement and means for imparting an axial movement to an upper die which has received a wet formed article toward a lower die when the dies are in axial alinement to maintain the article between said dies under compression while the dies move in the circular path.

7. A pulp molding machine comprising a shaft, means for imparting a step-by-step rotation thereto, a first series of drying dies and a second series of complementary drying dies mounted on the shaft in angularly spaced relation and rotating with the shaft, one of said series being connected with the shaft to travel in a circular path, means for guiding the other series of dies in the same circular path during a substantial portion of the rotating cycle of the shaft in axial alinement with the complementary series of dies laterally and for guiding said other series of dies out of and into said circular path during another portion of the rotating cycle of the shaft, each of the dies of one of said series of drying dies being arranged to receive a wet formed article when it is out of said circular path, said guiding means being arranged to return the dies into axial alinement and means for imparting relative axial movement to complementary dies when said dies are in axial alinement to maintain the article between them under compression while the dies move in the circular path and for separating the dies, and means for discharging the article when they are out of said circular path.

8. A pulp molding machine comprising a shaft, means for imparting a step-by-step rotation thereto, a series of upper drying dies and a complementary series of lower drying dies mounted on the shaft in angularly spaced relation and rotating with the shaft, said lower series being connected with the shaft to travel in a circular path, means for guiding the upper series of dies in the same circular path during a substantial portion of the rotating cycle of the shaft in axial alinement with the lower series of dies and for guiding the upper series of dies laterally out of said circular path during another portion

of the rotating cycle of the shaft, each of the dies of the upper series being arranged to receive a wet formed article when it is out of said circular path, said guiding means being arranged to return the dies into axial alinement, means for imparting an axial movement to an upper die which have received a wet formed article, toward a lower die when said dies are in axial alinement to maintain the article between them under compression while the dies move in the circular path and separating the dies, and means for discharging the article when they are out of said circular path.

9. A pulp molding machine comprising a shaft, means for imparting a step-by-step rotation thereto, a plurality of pairs of drying dies mounted on the shaft in angularly spaced relation and rotating with the shaft, means for imparting a relative movement to the dies of each pair to put them out of axial alinement with each other, a plurality of forming dies, one of each pair of said drying dies being arranged to receive a wet formed article from a forming die while out of axial alinement with its mating drying die, said moving means being arranged to return the drying dies into axial alinement, and means for imparting relative axial movement to said driving dies to compress the wet article between them.

10. A pulp molding machine comprising a shaft, means for imparting a step-by-step rotation thereto, a plurality of pairs of drying dies mounted on the shaft in angularly spaced relation and rotating with the shaft, means for imparting a relative movement to the dies of each pair to put them out of axial alinement with each other, a plurality of forming dies and a transfer die, one of each pair of said drying dies being arranged to receive a wet formed article from a forming die while out of axial alinement with its mating drying die, said moving means being arranged to return said drying dies into axial alinement, means for imparting relative axial movement to said drying dies to compress the wet article between them and for separating the dies, and means for discharging the article onto the transfer die while the dies are out of axial alinement.

11. A pulp molding machine comprising a shaft, means for imparting a step-by-step rotation thereto, a plurality of pairs of drying dies mounted on the shaft in angularly spaced relation and rotating with the shaft, means for imparting a relative movement to said drying dies of each pair to put them out of axial alinement with each other, a plurality of forming dies, a searing die, means for moving the searing die against and away from an article on one of the forming dies, one of said drying dies being arranged to receive a seared article from a forming die while out of axial alinement with its mating drying die, said moving means being arranged to return the drying dies into axial alinement, and means for imparting relative axial movement to said drying dies to compress the article between them.

12. A pulp molding machine comprising a shaft, means for imparting a step-by-step rotation thereto, a plurality of pairs of drying dies mounted on the shaft in angularly spaced relation and rotating with the shaft, means for imparting a relative movement to the dies of each pair to put them out of axial alinement with each other, a plurality of forming dies, a searing die, means for moving the searing die against

and away from articles on the forming dies in succession, a transfer die, one of each pair of said drying dies being arranged to receive a seared article from a forming die while out of axial alignment with its mating drying die, said moving means being arranged to return the drying dies into axial alignment, means for imparting relative axial movement to said drying dies to compress the article between them and for separating the dies, means for discharging the article onto the transfer die while the drying dies are out of axial alignment, and means for discharging the article from the transfer die.

13. A pulp molding machine comprising a forming unit shaft carrying a series of foraminous dies for suction formation of wet molded pulp articles, a drying unit shaft angularly disposed in relation to the forming unit shaft carrying a series of pairs of heated complementary drying dies in an arcuate path offset from the path of movement of the forming dies, adapted to compress a wet article therebetween and dry same under heat and mechanical pressure, a transfer die offset from the arcuate path of movement of the forming dies and from the arcuate path of movement of the drying dies, means for imparting a step-by-step rotation to said shafts to move the dies thereon from position to position with stationary intervals between said movements, means for moving one of each pair of drying dies into axial alignment with a forming die, back into axial alignment with its complementary drying die and out of its arcuate path into axial alignment with the transfer die, and means for bringing said last mentioned drying die successively into and out of coactive relation with said forming die, its complementary drying die and the transfer die.

14. A pulp molding machine comprising a forming unit shaft carrying a series of foraminous dies for suction formation of wet molded pulp articles, a drying unit shaft angularly disposed in relation to the forming unit shaft carrying a series of pairs of heated complementary drying dies in an arcuate path offset from the path of movement of the forming dies, adapted to compress a wet article therebetween and dry same under heat and mechanical pressure, a transfer die offset from the arcuate path of movement of the forming dies and from the arcuate path of movement of the drying dies, means for imparting a step-by-step rotation to said shafts to move the dies thereon from position to position with stationary intervals between said movements, means for moving one of each pair of drying dies into axial alignment with a forming die, back into axial alignment with its complementary drying die and out of its arcuate path into axial alignment with the transfer die, means for bringing said last mentioned drying die successively into and out of coactive relation with said forming die, its complementary drying die and the transfer die, means for effecting the transfer of a wet formed article from a forming die to the drying die which is in axial alignment therewith, and means for effecting the transfer of a dried article from said one of the drying dies to the transfer die.

15. A pulp molding machine comprising a forming unit shaft carrying a series of foraminous dies for suction formation of wet molded pulp articles, a drying unit shaft angularly disposed in relation to the forming unit shaft carrying a series of pairs of heated complementary

5 drying dies in an arcuate path offset from the path of movement of the forming dies, said drying dies being adapted to compress a wet article therebetween and dry same under heat and mechanical pressure, a transfer die offset from the arcuate path of movement of the forming dies and from the arcuate path of movement of the drying dies, means for imparting a step-by-step rotation to said shafts to move the dies thereon from position to position with stationary intervals between said movements, means for moving one of each pair of drying dies into axial alignment with a forming die, back into axial alignment with its complementary drying die and out of its arcuate path into axial alignment with the transfer die, means for bringing said last mentioned drying die successively into and out of coactive relation with said forming die, its complementary die and the transfer die, means for effecting the transfer of a wet formed article from a forming die to the drying die which is in axial alignment therewith, means for effecting the transfer of a dried article from said one of the drying dies to the transfer die, and means for discharging the article from the transfer die.

16. A pulp molding machine comprising a forming unit shaft carrying a series of foraminous dies for suction formation of wet molded pulp articles, a drying unit shaft angularly disposed in relation to the forming unit shaft carrying a series of pairs of heated complementary drying dies in an arcuate path offset from the path of movement of the forming dies, adapted to compress a wet article therebetween and dry same under heat and mechanical pressure, a transfer die offset from the arcuate path of movement of the forming dies and from the arcuate path of movement of the drying dies, means for imparting a step-by-step rotation to said shafts to move the dies thereon from position to position with stationary intervals between said movements, means for moving one of each pair of drying dies into axial alignment with a forming die, back into axial alignment with its complementary drying die and out of its arcuate path into axial alignment with the transfer die, means for bringing said last mentioned drying die successively into and out of coactive relation with said forming die, its complementary drying die and the transfer die, means for effecting the transfer of a wet formed article from a forming die to the drying die which is in axial alignment therewith, means for effecting the transfer of a dried article from said one of the drying dies to the transfer die, means for treating the article while it is on the transfer die, and means for discharging the article from the transfer die.

60 17. A pulp molding machine comprising an intermittently rotatable vertical drying unit shaft, a spaced series of upper drying dies adapted to receive wet formed molded pulp articles and a series of coacting complementary lower drying dies, both of said series of dies being mounted on and revolving with said shaft, said lower drying dies corresponding in number and angular spacing to said upper drying dies, means for rotating said shaft step-by-step, means for placing wet formed articles on said upper drying dies, means for coacting each upper drying die with a wet article thereon with its complementary lower drying die during a substantial portion of the rotating cycle of said shaft to dry the article between said pair of drying dies under heat and longi-

tudinal mechanical pressure, means for discharging the dried articles from said upper drying dies at the completion of the drying cycle, and means for displacing a drying die laterally from the path of coactive movement of its complemental drying die during those portions of the rotating cycle of said shaft at which a wet formed article is being placed on an upper drying die and at which each upper drying die is discharging a dried article.

18. A pulp molding machine comprising a rotary step-by-step forming unit shaft carrying a series of foraminous forming dies for the suction formation of wet molded pulp articles, an intermittently rotating drying unit shaft having its axis of rotation disposed substantially at right angles to the axis of rotation of said first named shaft and carrying a series of spaced upper drying dies and a complemental series of lower drying dies corresponding in number and angular spacing to the upper drying dies, a series of foraminous transfer dies for receiving and ejecting dried articles from the machine, means for rotating said shafts step-by-step in synchronism to bring the forming dies and the transfer dies into coactive alinement with the upper drying dies for the successive transfer of wet articles from said forming dies to said upper drying dies and dried articles from said upper drying dies to said transfer dies, means for successively imparting coacting lateral movements to each upper drying die first to coat said upper drying die with a forming die while said dies are at rest in their revolution about the axis of the drying unit shaft for transferring a wet article to the upper drying die and then to coat said upper drying die with its complemental lower drying die for drying the article under continuous heat, pressure and vacuum between said drying dies for a substantial portion of the rotating cycle of said drying unit shaft and subsequently to coat said upper drying die with a transfer die while said dies are at rest in their revolution, for transferring the dried article from the upper drying die to a transfer die, and means for relatively displacing the drying dies so that one is out of the path of the reciprocal movement of the other die during the period in which the reciprocating drying die is removing a wet article from a forming die and is transferring a dried article to a transfer die.

19. A pulp molding machine comprising a rotary step-by-step forming unit shaft, a foraminous forming die for the suction formation of a wet molded pulp article mounted on and revolute with said shaft, a rotary step-by-step drying unit shaft mounted adjacent to but independently of said forming shaft, a pair of drying dies complemental in size and shape mounted on and revolute with said drying unit shaft, one of said drying dies being reciprocably mounted relative to the other drying die, means for rotating both of said shafts step-by-step in synchronism with each other to bring the forming die and one of the drying dies into positions of coactive alinement with each other, means operative while both of said shafts are at rest, for successively imparting reciprocating movements to one of said drying dies to first cause said die to coact with said forming die to thereby transfer a wet article to said drying die and thereafter to cause said dry-

ing die with the wet article thereon to coact with its mating drying die to thereby dry the article between said pair of drying dies under heat and mechanical pressure, means for subsequently discharging the dried article from one of said drying dies and means for relatively displacing the reciprocally mounted die laterally out of alinement with its mating drying die during the period in which the reciprocating drying die is removing a wet article from a forming die and at the time it is discharging a dried article.

20. The machine of claim 19 in which the means for subsequently discharging the dried article from the reciprocating drying die comprises a transfer die pivotally mounted relative to the reciprocating drying die to receive the dried article from the reciprocating drying die, and means for swinging said transfer die to a position for ejecting the dried article from the machine.

21. A pulp molding machine comprising a rotary step-by-step forming unit shaft, a foraminous forming die for the suction formation of a wet molded pulp article mounted on and revolute with said shaft, a rotary step-by-step drying unit shaft mounted adjacent to but independently of said forming unit shaft angularly disposed in relation to the forming unit shaft, a plurality of pairs of drying dies complemental in size and shape mounted on and revolute with said drying unit shaft, a transfer unit shaft having transfer dies mounted thereon for receiving a dried article from one of the drying dies and ejecting it from the machine, means for rotating all of said shafts step-by-step in synchronism with each other to bring a forming die and a transfer die into positions of coactive axial alinement with two of the drying dies, means operative while all shafts are at rest for imparting reciprocating movements of said two drying dies to cause one of said dies to coact with said forming die to transfer a wet article to said drying die, thereafter to cause the drying die with a wet article thereon to coact with its mating drying die to thereby dry the article between said dies under heat and mechanical pressure and finally to cause the drying die with the article thereon to coact with a transfer die to transfer the article to said transfer die for ejection from the machine, and means for relatively displacing one of the drying dies of each pair from axial alinement with its complemental die so that one is out of the path of reciprocation of the other during the periods in which the reciprocating drying die is removing a wet article from a forming die or is transferring a dried article to a transfer die.

22. The machine of claim 21 in which the means for displacing the drying dies comprises a die carrier laterally movable in respect to the drying shaft, a cam roll carried by said die carrier, and a fixed cam race with which said cam roll connects.

23. The machine of claim 21 in which the means for displacing the drying dies comprises a die carrier pivotally connected with the drying shaft, a sliding member connected to said carrier and provided with a cam roll, and a fixed cam race with which said cam roll coacts.
